(57) **CLAIM**

We claim the ornamental design for a cover for air purifier with humidifier, as shown and described.

DESCRIPTION

FIG. 1 is a perspective view of a cover for air purifier with humidifier showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof

FIG. 8 is a perspective view thereof, in a use condition; and,
FIG. 9 is a top plan view thereof, in a use condition.

The broken lines represent unclaimed portions of the cover for air purifier with humidifier and form no part of the claimed design.
